Primary Examiner — Cynthia Ramirez*Assistant Examiner* — Laura H Yu(74) *Attorney, Agent, or Firm* — Banner & Witcoff, Ltd.(57) **CLAIM**

The ornamental design for a shoe, as shown and described.

DESCRIPTION

FIG. 1 is a front perspective view of a shoe showing my new design;

FIG. 2 is a side view thereof;

FIG. 3 is an opposite front perspective view thereof; and,

FIG. 4 is an opposite side view thereof.

The claim is directed to the appearance of the zig-zag line as shown in the drawings. The broken lines depicting the remainder of the shoe form no part of the claimed design.
